UNITED STATES PATENT OFFICE.

JOHN WILLIAM BARLOW, OF LAWRENCE, MASSACHUSETTS.

LOOM-PICKER.

SPECIFICATION forming part of Letters Patent No. 339,836, dated April 13, 1886.

Application filed October 14, 1885. Serial No. 179,843. (No model.)

To all whom it may concern:

Be it known that I, JOHN WILLIAM BARLOW, of Lawrence, in the county of Essex, of the Commonwealth of Massachusetts, have invented a new and useful Improvement in Loom-Pickers; and I do hereby declare the same to be described in the following specification, and represented in the accompanying drawings, of which—

10 Figure 1 is a side view, and Fig. 2 an end elevation, of a picker provided with my invention, the nature of which is defined in the claims hereinafter presented. Fig. 3 is a perspective view of the staple-formed re-enforce hereinafter explained.

15 The picker shown in the said drawings is represented as having its body composed of two sheets, A and B, of rawhide, bent and arranged with respect to each other as represented in Fig. 2.

In carrying out my invention I have within the said body, and extending down from its rod-passage a, a metallic re-enforce, C, staple-formed in transverse section, as shown, it reaching from end to end of the said passage, and aiding in forming it. The top of such re-enforce is curved transversely to the arc of the circle of transverse section of the said passage. Into the re-enforce there extends the upper part of the internal sheet, A, of rawhide, such sheet also extending above and embracing the re-enforce on its two opposite sides in manner as represented, the whole being covered by the outer sheet, B. Rivets D 25 go transversely through the rawhide body and the metallic re-enforce C. The re-enforce not only strengthens the body and supports the said rivets to advantage to prevent them from working loose, but covers the upper end 30 of the inner rawhide layer, so as to prevent it from being worn or broken down while the picker may be in use on its supporting-rod.

The re-enforce enables the passage a to be made cylindrical in form, and not only aids in preserving the passage in its normal condition while the picker may be at work, but is advantageous in other respects.

Within the rawhide core or plug E in the lower part of the body I insert a metallic re-enforce, b, in the shape of a helix or volute, it consisting of a plate of sheet metal laid upon a sheet of rawhide, and with it bent around

in a helix so as to form the core. This compound core of rawhide and metal will last very much longer than a core of rawhide only. The rivet e, going through the core, is firmly supported by it. The volute re-enforce operates to prevent the core from spreading laterally under the blows of it on the nose of the shuttle when the picker is in use.

The body of the picker, with the exception of the core, is composed of two sheets or strips, A and B, of rawhide, one end of the inner one being introduced into and covered by the re-enforce C. At its other end the piece A is 50 scarfed, as shown at e, and lapped on a correspondingly-scarfed end of the piece B, such piece B being scarfed at each end, the scarfing of the outer end of it being shown at g. From the re-enforce C the piece A extends downward straight for a proper distance, thence around the core or plug E, thence upward against itself and the re-enforce, thence around to form with the said re-enforce the rod-passage a, thence downward 55 against the re-enforce, and is lapped on the upper scarfed end of the piece B, arranged as represented. The piece B is carried around and against the piece A, and is secured thereto and to the re-enforce by rivets going transversely through the picker.

I sometimes make each re-enforce of other proper material than metal, though metal in most cases is preferable.

I do not claim a loom-picker constructed as 85 shown in the United States Patent No. 156,459, and having a wedge-shaped piece of rawhide or other material inserted in it next and under its rod-passage. Nor do I claim such wedge-shaped piece of rawhide as arranged against 90 such passage and between the folds of the strip in which such passage is formed. Nor do I claim a rawhide picker made as shown in either of the United States Patents Nos. 177,641, 205,261, 207,739, as neither of such 95 pickers have in them any re-enforce made and arranged as hereinbefore described. In other words, I do not claim a rawhide picker having its head-plug composed of a piece of rawhide wound in a helix or scroll and provided with a fillet or extension in one piece with the rest of the plug and secured by rivets going through it and the body of the picker, as shown in said Patent No. 177,641. Nor do I claim a staple

formed of a piece of rawhide arranged within the body and forming with the middle layer of rawhide the rod-passage, and clasping such middle layer at its upper part, all being as shown in the said Patent No. 205,261. Nor do I claim a picker made of two rawhide sheets arranged flatwise one upon the other, and folded at their middles to form the eye or rod-passage, and the neck extending therefrom, all being as shown in the said Patent No. 207,739. Nor do I claim in a picker its rawhide plug composed of a strip of rawhide wound in a helix and encompassed by a sheet of metal extending around it but not within it, such being as represented in the United States Patent No. 135,253.

I claim—

1. A loom-picker made of two layers of rawhide and having a staple-formed re-enforce, substantially as described, in one piece of material arranged to extend within it from its rod-passage downward and embrace and cover the upper end portion of the inner of the two layers of rawhide comprising the body of such picker, and extend between it and the said rod-passage, all being essentially as represented.

2. A loom-picker having its body composed of two layers or sheets of rawhide, and within such body and next its rod-passage a staple-formed re-enforce, substantially as described, in one piece of material extending down from the said passage and embracing the inner layer of the body at and cover one end thereof, and extend between it and the passage, as set forth, and secured on the body by rivets going through it and such body, as represented.

3. A loom-picker having its body composed of two layers or sheets of rawhide, and within such body a core made, as described, of a sheet of rawhide and one of metal rolled together in a helix or volute, and a re-enforce staple formed substantially as described and extending down from the rod-passage and embracing the inner layer or sheet of such body at one end portion thereof, the said body, re-enforce, and core being connected by rivets going through them laterally, as represented.

JOHN WILLIAM BARLOW.
